(57) **CLAIM**

The ornamental design for a replacement tail lens assembly for pick-up truck, as shown and described.

DESCRIPTION

FIG. 1 is a right side perspective view of the replacement tail lens assembly of the present design;

FIG. 2 is a right side perspective view of the replacement tail lens assembly of the present design showing the cover of the tail lens assembly removed;

FIG. 3 is a front view of the replacement tail lens assembly of the present design;

FIG. 4 is a right side view of the replacement tail lens assembly of the present design;

FIG. 5 is a top sectional view of the replacement tail lens assembly of the present design; and,

FIG. 6 is a right perspective view of the replacement tail lens assembly of the present design showing the lens assembly installed on a pick-up truck.

The broken lines showing of the lens assembly in FIG. 5 and of the automobile in FIG. 6 are for illustrative purposes only and form no part of the claimed design.
